Inventor

Richard S. Clark-

United States Patent Office.

RICHARD S. CLARK, OF GREAT BEND, PENNSYLVANIA.

Letters Patent No. 76,303, dated April 7, 1868.

IMPROVEMENT IN ENVELOPES.

The Schedule referred to in these Letters Patent and making part of the same.

TO ALL WHOM IT MAY CONCERN:

Be it known that I, RICHARD S. CLARK, of Great Bend, in the county of Susquehanna, and State of Pennsylvania, have invented a new and useful Improvement in Letter-Envelopes; and I do hereby declare that the following is a full, clear, and exact description of the same, reference being had to the accompanying drawings, in which—

Figure 1, the envelope opened.

Figure 2, the same opened at the end.

Figure 3, the envelope closed.

The object of this invention is to provide an envelope that cannot be tampered with, when sealed, without becoming mutilated, torn, or disfigured.

This is done by cutting out the paper for the envelope so as to leave the small flap A upon the part to be gummed, which, when turned down, will fold over upon the face of the envelope, as shown in fig. 3. When the envelope is sealed it will be impossible to raise the sealed part, either on the face or back of the envelope, without mutilating it, and showing that it has been tampered with.

Should this safety-envelope be adopted by the Government, that part which laps over on the face of the envelope can have the postage stamped or printed thereon; and, should the envelope become useless, by wrong superscription or otherwise, the stamp can be detached, and used on any other envelope.

Fig. 2 shows the manner of cutting out the envelope when it is desirable to have it open at the end.

What I claim my invention, and desire to secure by Letters Patent, is—

The flap A, so placed upon the envelope as to fold over on to the face of the envelope, substantially as and for the purpose described.

RICHARD S. CLARK.
